ULTRA HIGH FREQUENCY TUBE

Ilia Emmanuel Mouromtseff, Montclair, and George Michael Dinnick, Bloomfield, N. J., assignors to Westinghouse Electric Corporation, East Pittsburgh, Pa., a corporation of Pennsylvania

Application October 29, 1941, Serial No. 416,934

10 Claims. (Cl. 250—27.5)

This invention relates to ultra high frequency tubes and is particularly directed to the provision of an oscillation generator of the vacuum type for generating ultra high frequency wave output. In part it is a continuation of our copending application, Serial No. 360,367, filed October 9, 1940.

Generation of ultra high frequency oscillations for one purpose or another is not in itself a difficult matter, but numerous limitations of control and output have been encountered. Prior art constructions utilizing vitreous envelopes and lead-in wires introduce inter-acting inductance and capacitance of such material import and magnitude as to prevent adequate tuning and to impair utilization of ultra high frequency output therefrom. The maximum frequency at which the conventional tube will operate is intrinsically limited more especially by the physical obstacles governing the proper inclusion and exclusion of inter-electrode and inter-lead capacity as well as inductance of the leads to the electrodes and other factors affecting inductance and capacity, since all such factors enter into the system by way of limitation of the frequency at which the tube will operate. For instance, the generation of ultra high frequency oscillations by known three-electrode tubes have their practical limits at approximately 500 to 600 megacycles per second for an output of relatively very few watts.

The basic reasons underlying the limitations of prior art conventional tubes have explanation and foundation in the finite transit time of electrons and in the physical and electrical difficulties encountered in construction of an adequate oscillating circuit and tube. On the one hand, attainment of the mentioned 600 megacycle per second power out-put requires use of high voltages which immediately injects necessity for a tube structure physically too large for practically combining it with other structural parts and apparatus. On the other hand, decrease of the inter-electrode capacity for increasing the upper frequency limit at which a tube will operate, involves the adverse characterizations of making the electrodes smaller, shorter and bringing the leads out of the envelope at different or considerably separated points. In this connection, it may also be said that the higher the frequency, the greater the adverse or damaging effect of the structural parts of the tube, since they offer a discontinuity in the oscillating circuit.

It has heretofore been proposed to provide a hollow-body resonator intimately connected with a vacuum tube so as to generate ultra high frequency oscillations by means of diode relation-

ship of parts of the resonator. Such a construction produces a continuous electron flow but is capable of generating essentially very low outputs at very low efficiency as weak oscillations are superimposed on top of the much stronger electronic current flowing continuously. The prior art construction relies upon the negative resistance of the continuous electron flow with transit time equal to $\frac{1}{4}$, $\frac{1}{2}$, $\frac{1}{3}\frac{1}{4}$, etc., of the duration of an oscillating cycle. The present invention is a distinct advance over such a prior art construction in that we utilize a triode built into an efficient resonator and produce an electronic current which flows periodically when the grid voltage does not cut it off.

An object of the present invention is to provide a three-electrode oscillator with a single hollow-body resonator without discontinuity.

A further object of the invention is to provide 20 a generator of ultra high frequency waves comprising a tuned circuit enclosed within and including its envelope as part of the circuit.

A further object of the present invention is to obtain oscillation by an inductance-capacitance 25 circuit completed within the device.

A further object of the present invention is to provide electrodes which are inherently portions of an oscillating circuit without intervening conducting leads.

30 A further object of the present invention is to provide a high frequency oscillator capable of efficiently establishing a high frequency output.

Another object of the invention is to enable the oscillator to be tuned within a certain narrow 35 band of frequencies.

Another object of the invention is to vary the frequency, within limits, without necessity of opening the envelope.

40 A further object of the invention is to expedite control of the oscillating frequency of ultra high frequency electron discharge devices.

A still further object of the invention is to incorporate the electrode elements within a metallic resonator both for benefits above-given and to 45 prevent external radiation.

Yet again, an object of the invention is to provide a mechanically robust construction of self-contained ultra high frequency oscillator.

Further objects of the invention include provision of a structure adaptable to better cooling, simplicity of fabrication, stability of operation, and other advantages and results which will appear to those skilled in the art, both by direct statement thereof and by implication from the 55 context.

In the accompanying drawing, wherein like numerals of reference indicate similar parts throughout the several views, and wherein a preferred physical embodiment of the invention is disclosed by way of example:

Figure 1 is a vertical longitudinal sectional view of a high frequency oscillator of the character indicated and illustrative of the invention; and

Figure 2 is a cross-sectional view thereof on line II—II of Fig. 1.

In the specific embodiment of the invention illustrated in said drawing, the reference numeral 10 indicates a preferably right-cylinder hollow body constituting both an evacuated envelope and a resonator. Said envelope-resonator 10 preferably includes as its outer shell a metallic cylindrical outer side wall 11 and coaxial therewith an inner elongated reentrant tubular portion 12. The forward reentrant end of this said inner portion is formed in suitable manner as a mesh or perforate flat grid 13. Below the grid and within said inner or reentrant tubular portion 12 is a cathode 25. What may be termed for convenience in description as the upper or forward end wall of the cylinder in proximity to and parallel to said grid, is shown as a separately formed peripherally flanged end or cover member 14 of this rigid metallic construction. Next the inner face of this cover member and of substantially the same diameter thereas so as to nest therein, is a flexible metallic diaphragm 15. As to this feature, the present invention is in part a continuation of our former copending application, Serial No. 360,367, filed October 9, 1940. Said diaphragm likewise may be peripherally flanged but with its flange of less depth than that of the cover member. The flange of the diaphragm is preferably vacuum sealed peripherally to the side wall 11 of the cylinder next its end, as by silver soldering or otherwise. Cathode, grid and anode accordingly are present as a tube triode, with a portion of the grid and anode structures also forming a resonator chamber.

The flange of the cover member 14 may be given a threaded engagement with the marginal end portion of the cylinder and thus form a closure for the end of the cylinder and effect a clamping of the peripheral margin or flange of the diaphragm in place and prevent the vacuum seal from becoming disrupted in use. After assembly of these several parts as just described, the threaded joint between the cover flange and the cylindrical side wall 11 also may be rendered vacuum tight, if desired, by silver soldering or otherwise.

The diaphragm 15 is resilient and is inherently flat across its body portion, but may be flexed or convexed centrally inward toward grid 13 by means such as a thumb-screw 16 situated centrally of and through said cover member 14. Spacing between grid and diaphragm may accordingly be delicately adjusted and with the diaphragm functioning as an anode, tuning of the resonator is effected.

At what may be termed the bottom of the envelope is a metallic bottom plate or wall 17 parallel to the cover member. Said bottom plate is annular, and receives the reentrant tubular portion 12 through its central opening. As a convenient mode of fabrication, the lower end of said tubular portion is provided with a radially outwardly projecting peripheral flange 18 which is brought flatwise against the under side of the bottom plate or wall 17 and vacuum-

sealed thereat as by welding, brazing, silver soldering or otherwise. Suffice it to say that said tubular portion and bottom plate constitute a physical and electrical entity.

The outer periphery of the bottom plate 17 is flanged downward, as at 19, and feather-edged, said flange being of slightly less diameter than the inner diameter of the cylinder wall 11 so the flange and end margin of said cylinder wall will constitute a capacitance. A dielectric bead 20 overlies and enters between said flange and end margin of the cylinder wall both to maintain the spacing thereof and to provide a vacuum seal thereat. Said bead may conveniently be composed of boro-silicate glass and the end margin of the cylinder wall therein may likewise be feather-edged or otherwise sealed to glass as by use of "Kovar". Preferably the faces of the cylinder wall and flange which are toward each other are parallel for obtaining optimum capacitance relation.

A metallic nipple 21 is silver soldered or otherwise vacuum sealed with respect to the tubular portion 12 and protrudes from the lower end thereof, said nipple having its lower end tapered to a featheredge and sealed in a reentrant glass stem 22, the press end 23 whereof is well within and shielded by the said tubular portion. Lead-in wires 24 pass upwardly through the reentrant glass stem and press and support and feed an electron emitting cathode 25 somewhat below the grid and parallel thereto. Source of electrical energy (not shown) is applied across the terminals for the lead-in wires 24, as usual. A battery 26 is shown applying a grid bias from connection with one cathode lead and a connection 27 to nipple 21, which, with tubular portion 12 (both of which are metal) gives electrical communication to the grid. Plate potential is shown applied by battery 28 between the grid terminal and an anode terminal connection 29 secured to the cylindrical wall 11.

Output of derived high frequency energy is obtained through the agency of a coupling loop 30 near the bottom of the resonator chamber and formed as part of an output concentric line 31 suitably vacuum sealed at its place of entry through the cylinder wall.

It may now be called to particular attention that the device provides a construction having no sealed-in leads for grid or anode, but that the capacitance and inductance therebetween is confined to that produced directly by the grid and anode themselves. The structure includes, briefly, a right-cylindrical portion with which is associated a tubular reentrant portion having a flat grid with the cylindrical and tubular portions forming a hollow-body resonator chamber and a blocking capacitance. The grid has tunable relation to a resilient flexible anode forming as well one end of the resonant chamber. The inductance of the parts comprising the chamber enclosure resonant to the frequency at which the device is intended to operate, in combination with the self-contained capacitance, provides an inductance-capacitance oscillating circuit.

A stream of electrons emitted by cathode 25 passes through grid 13 at a velocity determined by the voltage of battery 26. The potential differences involved in the high frequency field of the resonator, however, are related to the oscillating grid potentials which should not be confused with the unvarying voltages, such as the grid bias, since the unvarying voltages have no

cyclic variation. The system shown is rendered oscillatory and productive of high frequency energy from bunching of energy-giving electrons. The cathode is spaced from the grid a very small distance comparable to a fraction of the wave length so that electrons passing from cathode to grid (which occurs in greatest number when the grid is positive and in less number when the grid becomes negative) will gain energy from the grid circuit. These electrons complete their journey from grid to plate while the grid is more negative, the spacing of the grid and plate being small, commensurate to the cathode-grid spacing, and adjustable by the flexible plate or diaphragm, for that purpose. Energy accordingly is transferred to the resonant circuit, part applying as a feedback to maintain oscillation and the balance available for output purposes.

The hollow-body resonator shown of right-cylinder, reentrant construction is very suitable for oscillations of the above specified frequencies, and is particularly advantageous for accomplishment of objects of our invention when combined, as indicated to form a three-electrode discharge tube. The wave length λ generated by this structure and combination (as given by F. B. Llewellyn and A. E. Bowen in an article entitled "The production of ultra-high frequency oscillations by means of diodes," appearing in vol. 18 of The Bell System Technical Journal, of April, 1939, page 280 et seq.) may be found from the expression:

$$\frac{1}{\lambda} \tan \frac{2\pi h}{\lambda} = \frac{x}{\pi r_2^2 \log \epsilon_{r_2}}$$

where x represents the distance between grid and anode, and in analyzed cases must be very small. Other symbols employed in this equation are h , which is the inside resonator height; r_1 the inside radius of the larger cylindrical body portion; and r_2 the radius to the outer face of the reentrant cylindrical body portion 12. Accordingly a slight change of h by the flexible diaphragm 15, will produce a noticeable change in generated frequency. This structure beneficially eliminates one necessity to adjust the distances between the tube elements with an extreme accuracy when the device is assembled, and permits tuning to a fixed output circuit.

It may furthermore be stated that two such devices may be used butt to butt for push-pull operation, and that other modifications and changes in structure and use may be made without departing from the spirit or scope of the invention, and it is to be understood we do not limit ourselves to the details of description or drawing, except as set forth in the following claims.

We claim:

1. A hollow-body resonator providing an evacuated chamber for high frequency oscillations, comprising a metallic right-cylinder portion and a metallic reentrant portion, one of said portions providing a grid and the other portion providing an anode each an inherent part of the respective portions without discontinuity, a cathode adjacent said grid on the opposite side thereof from the anode, and means for deriving high frequency oscillating energy from the said chamber.

2. A hollow-body resonator providing an evacuated chamber for high frequency oscillations, comprising a metallic right-cylinder portion and a metallic reentrant portion, one of said portions

providing a grid and the other portion providing an anode each an inherent part of the respective portions without discontinuity, said grid and anode being substantially parallel to each other a small distance apart compared to the wave-length of the high frequency oscillations, and means for deriving high frequency oscillating energy from the said chamber.

3. A hollow-body resonator providing an evacuated chamber for high frequency oscillations, comprising a metallic right-cylinder portion and a metallic reentrant portion, one of said portions providing a grid and the other portion providing an anode each an inherent part of the respective portions without discontinuity, said portions constituting inductance and having juxtaposed areas separated by a dielectric and constituting a capacitance for introducing a self-contained inductance-capacitance oscillatory circuit in the resonator, a cathode adjacent said grid on the opposite side thereof from the anode, and means for deriving high frequency oscillating energy from the said chamber.

4. A hollow-body resonator providing an evacuated chamber for high frequency oscillations, comprising a metallic right-cylinder portion and a metallic reentrant portion, one of said portions providing a grid and the other portion providing an anode each an inherent part of the respective portions without discontinuity, a cathode adjacent said grid on the opposite side thereof from the anode, said grid and anode being substantially parallel to each other a small distance apart compared to the wave-length of the high frequency oscillations, and leads for said anode and grid connected electrically thereto by connection at the outside of the resonator body to the respective right-cylinder and reentrant portions, and means for deriving high frequency oscillating energy from the said chamber.

5. A hollow-body resonator providing an evacuated chamber for high frequency oscillations, comprising a metallic right-cylinder portion and a metallic reentrant portion, one of said portions providing a grid and the other portion providing an anode each an inherent part of the respective portions without discontinuity, said portions constituting inductance and having juxtaposed areas separated by a dielectric and constituting a capacitance for introducing a self-contained inductance-capacitance oscillatory circuit in the resonator, a cathode adjacent said grid on the opposite side thereof from the anode, leads for said anode and grid connected electrically thereto by connection at the outside of the resonator body to the respective right-cylinder and reentrant portions, and means for deriving high frequency oscillating energy from the said chamber.

6. A hollow-body resonator providing an evacuated chamber for high frequency oscillations, comprising a metallic right-cylinder portion and a metallic reentrant portion, said reentrant portion providing a flat grid across its innermost end and the other portion providing an anode at the inner end of said right-cylinder portion next said grid, said grid and anode each formed as an inherent part of the respective portions without discontinuity, said portions constituting a capacitance and having juxtaposed areas remote from the grid and anode and separated by a dielectric and constituting a capacitance for introducing a self-contained inductance-capacitance oscillatory circuit in the resonator, a cathode adjacent said grid on the opposite side there-

of from the anode, said grid and anode being substantially parallel to each other a small distance apart compared to the wave-length of the high frequency oscillations, leads for said anode and grid connected electrically thereto by connection at the outside of the resonator body to the respective right-cylinder and reentrant portions, and means for deriving high frequency oscillating energy from the said chamber.

7. A hollow-body resonator providing an evacuated chamber for high frequency oscillations, comprising a metallic right-cylinder portion and a metallic reentrant portion, one of said portions providing a grid and the other portion providing an anode each an inherent part of the respective portions without discontinuity, said anode comprising a diaphragm movable toward and away from the said grid; means exterior of the resonator body for adjusting the anode-grid spacing while maintaining evacuation of said resonator body, a cathode adjacent said grid on the opposite side thereof from said anode, and means for deriving high frequency oscillating energy from the said chamber.

8. A hollow-body resonator providing an evacuated chamber for high frequency oscillations, comprising a metallic right-cylinder portion and a metallic reentrant portion, one of said portions providing a grid and the other portion providing an anode each an inherent part of the respective portions without discontinuity, said anode comprising a peripherally flanged diaphragm having its flange vacuum-sealed to the said right-cylinder portion at one end thereof, said diaphragm being resiliently flexible and tending to assume a normally flat condition, an end cover member for said cylinder portion overlying said diaphragm, a screw through said cover engaging a mid part of said diaphragm for flexing said diaphragm inward toward the grid while maintaining evacuation of said resonator body, a cathode adjacent said grid on the opposite side thereof from said anode, and means for deriving high frequency oscillating energy from said chamber.

9. A hollow-body resonator providing an evacuated chamber for high frequency oscillations, comprising a metallic right-cylinder portion and a metallic reentrant portion, one of said portions providing a grid and the other portion providing a flexible anode, said portions constituting inductance and having juxtaposed areas separated by a dielectric and constituting a capacitance for introducing a self-contained inductance-capacitance oscillatory circuit in the resonator, a cathode adjacent said grid on the opposite side thereof from the anode, said grid and anode being substantially parallel to each other a small distance apart compared to the wave-length of the high frequency oscillations, means exterior of the resonator body for adjusting the anode-grid spacing while maintaining evacuation of said chamber, and means for deriving high frequency oscillating energy from the resonator body.
10. A hollow-body resonator providing an evacuated chamber for high frequency oscillations comprising a metallic right-cylinder portion and a metallic reentrant portion, one of said portions providing a grid and the other portion providing an anode, said anode comprising a resilient flexible diaphragm, a cover member over said diaphragm, said cover member and diaphragm forming a double end closure for said right-cylinder portion, screw means for flexing said diaphragm inward of said chamber toward the grid, said grid and anode diaphragm being substantially parallel to each other a small distance apart compared to the wave-length of the high frequency oscillations, a cathode adjacent said grid on the opposite side thereof from the anode, leads for said anode and grid connected electrically thereto by connection at the outside of the resonator body to the respective right-cylinder and reentrant portions, and means for deriving high frequency oscillating energy from the resonator body.
